UNITED STATES PATENT OFFICE.

GREGORY KOVALEVITCH, OF SOUTH PORTLAND, OREGON.

SHIP.

1,113,173.

Specification of Letters Patent.

Patented Oct. 6, 1914.

Application filed August 2, 1913. Serial No. 782,718

To all whom it may concern:

Be it known that I, GREGORY KOVALEVITCH, a subject of the Emperor of Russia, residing at South Portland, in the county 5 of Multnomah and State of Oregon, have invented new and useful Improvements in Ships, of which the following is a specification.

My invention relates to safety devices for 10 ships, or means to prevent the sinking of ships in case of injury causing leakage at sea.

The object of my invention is to produce the hull of a ship constructed of separable 15 sections adapted to be disunited to permit the leaking lower or keel section to be severed from the upper or superposed section and sink without carrying down the upper or superposed section.

20 A further object of my invention is to produce means for automatically closing the openings in the bottom of the upper section which communicate with the lower section before the lower section is released, and for 25 severing the smoke funnel above the lower section.

Another object thereof is to produce 30 means for tightly uniting the upper and lower sections of the ship and for quickly 35 and conveniently separating the sections when the lower section is filled with water to permit the lower section to sink from the upper section, and a still further object of my invention is to produce a more simple 40 and efficient device of said character than has heretofore been attained.

To these ends, my invention includes the combination and arrangement of component 45 parts to be hereinafter described and more particularly pointed out in the claims.

In the accompanying drawings, in which like reference characters indicate similar parts, Figure 1 is a side view of the hull 50 of my ship showing the separable sections united; Fig. 2 is a transverse sectional view of the same; Fig. 3 is a longitudinal sectional view showing the apparatus for operating the means for removably securing the upper 55 section to the lower section and the apparatus for severing the smoke stack and openings in the bottom of the upper section in normal position; Fig. 4 is a similar view showing said apparatus as actuated to release the lower section to sink, sever the 60 smoke stack and close the openings in the

upper section; Fig. 5 is a transverse sectional view of my ship taken on the line 5—5 of Fig. 3; Fig. 6 is a similar view taken on the line 6—6 of Fig. 3, and Fig. 7 is a detail view of the latches for holding the 60 sections of my ship united. Fig. 8 is a detail of the mechanism for severing the smoke stack.

Referring now to the drawings, 1 indicates the lower or keel section of the hull of 65 my ship and 2 designates the upper or superposed section. The two sections are fitted together around their outer edges by a water-tight tongue and groove joint 3, and the lower section is secured upon the upper 70 section by a plurality of upright stays 5 embracing the sides of the upper section and secured by releasable latches 6 on the upper section to be hereinafter described.

The driving machinery of the ship, if it 75 be a power driven vessel, may preferably be carried in the lower section 1, and the upper section 2 is provided with a bottom 7 having a hatch 8 therein to communicate with the lower section, and with one or more 80 ventilator openings 8' to admit the supply of fresh air to the lower section.

The upper ends of the uprights 5, as before stated, are held on the upper section 85 by the releasable latches 6, which preferably comprise the pivoted members 40 over one end of which the ends of the uprights are looped, while the opposite ends of the pivoted members are held down by the pawls 9 pivoted at one end on the pivoted 90 arms 10, and the free ends 9' bear upon the free ends of the pivoted members 40 and engage the notches 7' therein. The upper or free ends of the pivoted arms 10 are connected by the rods 11 and 11' on the opposite 95 sides of the vessel. Said rods are connected at one end with the levers 12 and 12' by the links 13 and 13', and the levers may be locked and properly protected to prevent tampering by unauthorized persons. 100 When leakage in the lower section requires its release to save the superposed section, the levers 12 and 12' may be thrown, as shown in Fig. 4 of the drawings, which releases the pawls 9 from contact with the free 105 ends of the pivoted members 40 and releases the uprights 5 to drop and the lower section to sink from beneath the upper section.

The smoke stack 4, may be made of two 110 jointed sections, and passes through the

hatch 8, and the two sections may be separated prior to the separation of the two sections of the hull by automatic means, and the hatch 8 and the ventilator opening 8' closed by automatic means actuated by the rise of water in the lower hull section, which I will now proceed to describe.

Vertically disposed within the lower section 1 of the hull, is carried the hollow shaft 14 in which is loosely carried the float 14'. The lower end of the shaft is open to permit the ingress of water. The float 14' is connected by the stem 14'' with the lever 15 which is pivoted intermediate its ends at 15', and which is adapted at its opposite end to normally support the pivoted weight 16. Said weight is pivotally suspended upon the frame of the lower section, and is connected with the pivoted lever 17 at one end while the opposite end is connected with the sectional smoke stack 4, and is adapted when the float is elevated in the shaft, and the weight 16 is released as shown in Fig. 4, to sever the sections of the stack.

For the purpose of communicating fresh air through the ventilator opening 8', I provide the flue 18 passing vertically through the upper section and discharging into the lower section. For the further purpose of automatically closing the ventilator port 8', I provide the trap door 20 pivoted beneath the bottom of the upper section and adapted to normally swing downwardly. Said trap-door may be automatically closed 35 by the counter-weighted bell-crank lever 21, the unweighted end of which is adapted to bear upon the lower face of the trap. Said lever is fulcrumed at 21' on the outer face of the bottom of the upper section 2, and 40 is normally held in open position shown in Fig. 3 of the drawings by the latch 22' on the end of the pivoted lever 22, which engages the weighted end of the lever 21'. Said lever is operated to release the latch 45 by the float 23 to which it is attached, and which float is loosely carried in the hollow shaft 24. Said float is so positioned that it will not be actuated to operate the lever until the water in the hold has risen higher 50 than was required to effect the separation of the smoke stack.

As shown in the drawings, the upper face of the trap-door 20 is provided with an upright stud 25 having a notched head 25' adapted to be engaged by the pawls 26 carried on the transverse bar 27 which is pivoted at one end on one side of the port while the opposite end is engaged by the end 28' of the pivoted and weighted lever 60 28. Said lever 28 is normally held upright by the frame 29 to which it is latched at its upper end, but when the trap is closed as before described, the latch is released and the weighted end 28' is released to drop 65 downwardly and exert a lifting pressure

upon the trap door and press it upwardly upon the lower face of the bottom of the upper section of the hull.

The hatch 8 in the bottom of the upper section is closed by the pivoted trap-door 31, operated by the bell-crank lever 32, which is controlled and actuated by the float 33 and lever 34, all corresponding in construction to the similar parts for closing the ventilator port 8' before described. On the top of the trap-door 31, however, is attached a transverse bar 35, the free end of which, when the door is closed, strikes and raises the latch 36 which holds the weighted lever 37 inactive, and the under face thereof is notched at 35' to be engaged by the lifting end of the lever 37 to tightly close the door upon the bottom of the upper section and prevent leakage through the hatch.

Having thus described my invention, what I claim as new, and desire to be secured by Letters Patent, is—

1. The hull of a ship, comprising separable upper and lower sections, means for removably securing said sections together, a bottom for the upper section having openings therein communicating with the lower section, water-tight closures for said openings, and means actuated by the rise of water in the lower section for operating said closures.

2. In a sectional hull for ships, the combination with a keel section, of a superposed section separably mounted thereon and jointed thereto, a bottom for the superposed section having an opening therein, a trap-door for closing said opening, a weighted lever for closing said door, a latch for normally holding said lever inactive, a float carried in the keel section and connected with said latch adapted to be actuated by the rise of water therein to trip the latch and release said weighted lever to close the trap-door, substantially as described.

3. In a sectional hull for ships, the combination with a keel section, of a superposed section separably mounted thereon and jointed thereto, a bottom for the superposed section having an opening therein communicating with the lower section, a hinged door for closing said opening, a weighted lever for closing said door, a latch for normally holding said lever inactive, a float carried in the keel section and connected with said latch adapted to be actuated by the rise of water therein to trip the latch and release said weighted lever to close the door, a latch for locking said door shut, a pivoted lever for pressing the door tightly closed to form a water-tight closure, and a latch for normally holding said last mentioned lever inactive and adapted to be tripped by the closing of the door to release the lever, substantially as described.

4. In a sectional hull for ships, the combi-

nation with a keel section, of a superposed section separably mounted thereon, a bottom for the superposed section having an opening therein, a sectional smoke funnel 5 passing through said opening, a pivoted weight mounted on the lower section and connected at one end to the lower section of the funnel, a latch for normally holding said weight elevated, a float carried on said 10 lower section and connected with said latch adapted to be actuated by the rise of water in the lower section to operate the latch to release said pivoted weight to disconnect the sections of the funnel, substantially as described.

5. In a sectional hull for ships, the combination with a keel section, of a superposed

section separably mounted thereon, a bottom for said superposed section having a ventilator opening and a hatch-way therein, 20 a separable smoke funnel passing through said hatch-way, closures for said ventilator opening and hatch-way, means for operating said closures and separating said sectional smoke-funnel, and floats carried in hollow 25 shafts in said keel section adapted to be successively actuated by the rise of water in the keel section to operate said stack-separating means and said closing means, substantially as described.
